LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

DISPENSING UNIT EMBODYING MECHANICAL REFRIGERATION

Application filed April 30, 1928. Serial No. 273,786

This invention relates to dispensing units embodying mechanical refrigeration, and has to do particularly with a very compact, inexpensive and simple structure of the water cooler type and the manner of arranging the cooling unit adjacent the container whereby to effect an extremely efficient refrigerating system having excellent heat conducting as well as hold-over properties.

not only has a very sanitary appearance but is very efficient as a heat conductor and as a hold-over. This container 1 is preferably unitary and rectangular, although it may be understood that it may assume various shapes in accordance with the invention. The top of the container 1 may be closed by a suitable closure member 2, or such member 2 may be so constructed as to receive the usual standard water bottle.

10 The liquid container is preferably formed or cast in one piece and of a material different than the remaining part of the unit. The refrigerating or cooling unit is preferably of the flooded type consisting of a boiler or
15 evaporator and a plurality of heat conducting members branching off therefrom to embrace and be positioned in heat conducting relation with the sides of the liquid container. The cooling unit, together with the additional
20 heat conducting means, may be embedded in place by enclosing the same with plasticly applied stone, or the stone may be so molded as to form suitable passageways for permitting the movement of the cooling unit.

The refrigerating effect is preferably secured by a suitable boiler or evaporator 3 which may be of standard design and suitably constructed to receive liquid refrigerant from a source (not shown) and maintain the same at a given level. This cooling unit 3 is provided with branch members 4 and 5 which preferably extend up alongside of the two walls of the member 1. 55
60

25 In the drawings:

Fig. 1 is a perspective view, partly cut away, of a portion of a dispensing unit embodying the present invention.

Fig. 2 is a vertical sectional view illustrating in particular the manner of positioning and arranging the cooling unit and the heat conducting branch members thereof relative to the liquid container.

Fig. 3 is a plan view, partly cut away, of the structure shown in Fig. 2, and illustrating the branch heat conducting members in the form of conduits for assisting the circulation of the refrigerating medium.

Fig. 4 is a plan view similar to Fig. 3 illustrating a modified form of structure in that the branch conduits are solid heat conducting members.

The liquid container or main dispensing unit comprises a member 1 which is preferably formed of fired ceramic material which

Such cooling unit and the branch heat conducting members 4 and 5 are preferably held in heat conducting relation with the container 1 by means of the stone lining 6 which may be formed of an oxy-chloride cement or other suitable unfired material. Such stone 6 may be initially molded so as to present a suitable opening for receiving and supporting the member 3 with the branch members 4 and 5 whereby such member may be removed or replaced as a unit. Or if desired, when the member 3 is once placed in position, the stone 6 may be plastically applied to securely embed the same in position. This plastically applied but hardened stone 6 is preferably of sufficient mass to act as a good hold-over, and while it has good heat conducting properties, the branch members 4 and 5 have relatively greater heat conducting properties whereby to effect a more rapid heat distribution.

A suitable spigot member 7 may be positioned to dispense the contents from the container 1, and although such member is shown in position at the side in Fig. 2, this is merely for illustration and in its preferred form it

is positioned in the front, and at one side, of the container. The stone work lining 6 is of course preferably surrounded by suitable insulating material 8 to form the cabinet of an entire cooling unit.

5 In the modification shown in Fig. 4, the cooling unit 3 is provided with suitable metallic fins 9 and 10 for effecting a greater transfer of the heat than would be otherwise obtainable by the cast stone. Such fins 9 and 10, together with the unit 3, may be embedded by the plastically applied stone into permanent heat conducting relation with the container 1, or the stone may be so molded as 10 to slidably receive the member 3 with the fins 9 and 10 if desired. In case the member 3, together with its heat conducting branches, 15 is embedded in the stone, the unit 1 is preferably removable whereby to permit of access to the cooling unit.

20 In the operation of the unit, a suitable refrigerant is conducted to the evaporator 3, according to temperature conditions, and cooling of the liquid within the container 1 is effected by direct heat conduction through 25 the container 1 and between the member 3 and its branches extending up and around the container, and the liquid within the container. Such branch members 4 and 5, or 9 and 10, in combination with the stone container and stone lining, effecting efficient heat 30 conduction entirely around the container unit to evenly distribute and equalize the heat units. This will permit the refrigeration 35 system to be run at a much higher temperature to thus greatly increase the efficiency thereof. The stone container 1 and the stone lining 6, while they both act as good conductors, are also efficient hold-over mediums to materially reduce the frequency of the 40 operation of the unit.

45 What I claim is:

1. A refrigerating apparatus of the liquid dispensing type, comprising an integral container for receiving the liquid to be cooled and dispensed, an evaporator positioned in heat conducting relation with one of the walls of said container for receiving and circulating a volatile refrigerant, and heat conducting branch members extending from 50 said evaporator in heat conducting relation with other walls of said container whereby to effect equalization in the cooling of said liquid contents.

55 2. A refrigerating apparatus of the liquid dispensing type, comprising a cast stone container unit for receiving the liquid to be dispensed, a cooling unit, a plastically applied stone work lining between the container 60 and the cabinet walls of the apparatus, and a portion of said stone container and said stone lining being spaced for receiving said cooling unit and positioning the same in heat conducting relation with the container.

65 3. A refrigerating apparatus of the liquid

dispensing type, comprising a liquid container, a cooling unit comprising an evaporator positioned in heat conducting relation with a portion of the container, and branch heat conducting means leading therefrom and 70 positioned in heat conducting relation with other parts of the container to effect uniform distribution of heat, and an artificial stone of the type adapted to harden without firing surrounding and holding said evaporator and branch members in position.

4. A refrigerating apparatus of the liquid dispensing type, comprising a liquid container, a mass of stone surrounding said container and providing a space therebetween, and a cooling unit for receiving a volatile refrigerant slideable in the space between the container and stone, said cooling unit being 80 in heat conducting relation with the container, and said mass of stone being such as to 85 serve as a good hold-over.

5. A refrigerating apparatus of the liquid dispensing type, comprising a container for receiving a liquid to be dispensed, a cooling unit comprising an evaporator for receiving and circulating refrigerant positioned in heat 90 conducting relation adjacent one part of said container, branch pipes leading from said evaporator and extending around and in heat conducting relation with other portions of 95 said container, and a material having good hold-over properties surrounding said evaporator and branch heat conducting members.

6. A refrigerating apparatus of the liquid dispensing type, comprising a unitary integral container of fired ceramic material for receiving a liquid to be dispensed, a cooling unit comprising an evaporator for receiving and circulating refrigerant positioned in heat conducting relation adjacent the bottom of said container, branch pipes 100 leading from said evaporator and extending upwardly around and in heat conducting relation with the side walls of said container, and a material having good hold-over properties surrounding said evaporator and branch heat conducting members, said evaporator and heat conducting members being 110 slideable in a space provided between said container and said hold-over material.

7. A refrigerating apparatus, comprising a container unit formed of fired ceramic material, artificial stone of the type adapted to harden without firing positioned around said container unit, said artificial stone being 120 formed to provide a space for receiving a refrigerant conducting member, said refrigerant conducting member being slideable in said space and being positioned in heat conducting relation with said container, and said 125 artificial stone serving as a hold-over.

8. A refrigerating apparatus of the liquid dispensing type, comprising a liquid container formed of a fired ceramic material, refrigerant conducting means positioned in 130

heat conducting relation with the bottom of
said container, and branch heat conducting
means extending from said cooling unit up-
wardly, around and in heat conducting rela-
tion with the sides of said container, and a
mass of material having good hold-over prop-
erties but of less heat conductivity than said
branch members for surrounding the cool-
ing member and its branch members, and
10 serving as a hold-over for the entire system.

5 In testimony whereof I affix my signature.
LLOYD G. COPEMAN.
